SUPPORT FOR FLEXIBLE POSTERS

Jay Noble Emley, Forest Hills, N. Y., assignor to
National Process Company, Inc., New York,
N. Y.

Application January 22, 1934, Serial No. 707,706

9 Claims. (Cl. 40—125)

This invention relates to what are known as flexible posters consisting of a flexible sheet of material having reinforcing or stiffening strips disposed at the ends thereof and particularly to a device for supporting such posters in extended position and upon a suitable support; and the object of the invention is to provide a supporting device or easel for posters of the class described involving two or more rods and a coupling plate in connection with which the rods are mounted so as to form a spring member of one rod or of a pair of rods coupled with the stiffening strips of the poster to support the poster sheet in extended or display position under the tension of said spring rod or rods and further whereby the other rod on said plate will form a supporting leg or easel for the complete device; a further object being to provide a coupling plate in which the rods are rotatably mounted to facilitate adjustment of the supporting leg with respect to the poster sheet in mounting the same in connection with or upon a suitable supporting surface; and with these and other objects in view, the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective rear view of a poster showing one of my improved supporting devices coupled therewith and indicating the method of its use.

Fig. 2 is an enlarged sectional detail view on the line 2—2 of Fig. 1.

Fig. 3 is an enlarged side and sectional view of a coupling plate which I employ, indicating the mounting of rods in connection therewith; and,

Fig. 4 is a view similar to Fig. 3 showing a modification.

In Fig. 1 of the drawing, I have shown at 5 a flexible poster sheet which may be composed of any suitable material upon which may be printed, lithographed, painted or otherwise applied display or advertising matter. Secured to the upper and lower ends of this sheet are reinforcing or stiffening strips 6 and 7 which may be composed of any suitable material and which in the construction shown are indicated as strips of wood having centrally thereof apertures 6a, 7a, to receive the ends of a spring member 8. The

member 8 in the construction shown in Figs. 1 and 3 consists of two parts or rods 8a and 8b, whereas in Fig. 4 of the drawing, said member consists of a single part of rod 8c. The rods 8a and 8b are connected with a coupling plate 9 having cylindrical sockets 9a and 9b for the rods 8a, 8b respectively, the sockets 9a and 9b being fortified by rolling or curling one edge of the plate 9 upon itself, and it is preferred that the portion of cylinder be crimped or compressed as indicated at 9c centrally thereof to limit the inward movement of the rods 8a and 8b as will be apparent.

The other side edge of the plate 9 is disposed angularly with respect to the edge including the sockets 9a, 9b and is curled to form a socket 9d extending or opening through the wide end of the plate to facilitate the attachment of a rod 10 with said socket 9d to form of the rod 10 the leg of the easel structure which consists of the member 8, plate 9 and leg 10. Inward movement of the rod or leg 10 with respect to the plate 9 is restricted by a compression of the curled cylinder or socket 9d as at 9e.

With the construction shown in Fig. 4, I employ 25 a modified form of coupling plate 11 which differs from the plate 9 simply in providing a continuous cylinder 11a at one side of the plate by curling said side edge of the plate, and this cylinder may be slightly arched or curved as indicated in Fig. 4 30 to compensate to some degree for the curvature of the spring rod or member 8c when mounted in position for use. It will be understood, however, that the curvature of the cylinder 11a is not absolutely necessary. The other side edge of the 35 plate 11 has a cylindrical socket 11b for receiving the leg 10, the latter being similar in all respects to the cylindrical socket 9d, the same being compressed as seen at 11c to limit inward movement of the leg or rod 10.

With the construction shown in Figs. 1 and 3 of the drawing, the supporting device or easel for the flexible poster is first assembled by coupling the rods 8a, 8b with the respective sockets employed on the plate 9, and then coupling the leg 45 rod 10 with its socket 9d, after which the end of one of the rods 8a, 8b is placed in the aperture 6a, 7a of one of the strips 6 and 7, and both rods 8a, 8b are then sprung outwardly and the opposed end is mounted in the aperture of the opposed 50 strip; and when coupled, the member 8 will assume a bowed position, maintaining the sheet 5 under tension, thus supporting said sheet in a straight and smooth position, forming a neat and finished appearance. It will be understood that 55

the leg 10 serves to support the poster in upright position on a table, floor or other surface, and by virtue of the mounting of the rods in connection with the plate 9, said plate may be rotated to 5 position the leg 10 at any desired angle with respect to the back of the poster to facilitate the placement of the poster.

- With the construction shown in Fig. 4 of the drawing wherein a single rod 8c is employed, it 10 will be apparent that the plate 11 will be capable of longitudinal movement on the bowed rod 8c when mounted in connection with the poster, thus facilitating the arrangement of the poster in different angular positions in the vertical plane. 15 At this time, it will also be apparent that the same result could be accomplished by having the leg member or rod frictionally engage its supporting socket in the plate 9, 10 to provide for adjustment of the leg 10 with respect to such plate. 20 This is especially true in view of the fact that the poster has no material weight to be supported by the easel.

It will be apparent that my invention is not necessarily limited to the mounting of the poster in the particular position indicated, nor am I necessarily limited to the particular form of the coupling plates herein disclosed nor to the number of rods employed in conjunction with said plate, and various changes in and modifications of the 25 structure shown and described may be made within the scope of the appended claims without departing from the spirit of my invention or sacrificing its advantages.

Having fully described my invention, what I 30 claim as new and desire to secure by Letters Patent, is:

1. A supporting device for posters of the class described comprising an elongated spring rod member adapted to engage the poster to support 35 the same in extended position, a coupling plate on said member substantially centrally thereof, a leg coupled with said plate and extending therefrom angularly with respect to said member, and said plate being rotatable on said member.
- 40 2. A supporting device for posters of the class described comprising an elongated spring rod member adapted to engage the poster to support the same in extended position, a coupling plate on said member substantially centrally thereof, a leg coupled with said plate and extending therefrom angularly with respect to said member, and said plate being rotatable on said member longitudinally thereof.
- 45 3. A supporting device for posters of the class described comprising a coupling plate, one side edge of which is curled to form a cylindrical socket and the other side edge having a curled cylindrical socket disposed angularly with respect to the first named socket, rods detachably coupled with the sockets of said plate, one of said rods having end portions projecting from both ends of the plate and adapted to engage the poster to support the same in extended position, and the rod attached to the other socket extending from one end of the plate only and adapted to form a supporting leg for said poster.
- 50 4. A supporting device for posters of the class described comprising a coupling plate, one side edge of which is curled to form a cylindrical socket and the other side edge having a curled cylindrical socket disposed angularly with respect to the first named socket, rods detachably coupled with the sockets of said plate, one of said rods having end portions projecting from both ends of the plate and adapted to engage the poster

to support the same in extended position, the rod attached to the other socket extending from one end of the plate only and adapted to form a supporting leg for said poster, and said plate being adjustable longitudinally of the first named rod to raise and lower the second named rod with respect to a support to vary the inclination of the poster on said support. 5

5. A supporting device for posters of the class described comprising a coupling plate, one side edge of which is curled to form a cylindrical socket and the other side edge having a curled cylindrical socket disposed angularly with respect to the first named socket, rods detachably coupled with the sockets of said plate, one of said rods having end portions projecting from both ends of the plate and adapted to engage the poster to support the same in extended position, the rod attached to the other socket extending from one end of the plate only and adapted to 10 form a supporting leg for said poster, said plate being adjustable longitudinally of the first named rod to raise and lower the second named rod with respect to a support to vary the inclination of the poster on said support, and said plate being rotatable on the first named rod in the different positions of adjustment thereof. 15

6. In an easel of the class described, an elongated coupling plate having angularly disposed side edges, one edge being at right angles to the ends of said plate and the other edge at an angle greater than ninety degrees to one of said ends, each side edge being curled to form a tubular socket, the tubular socket at each edge extending throughout the full length of the plate, or 20 edge thereof, the body portion of the plate joining the tubular sockets throughout the length of the plate, and independent rods mounted one in each tubular socket. 25

7. In an easel of the class described, an elongated coupling plate having angularly disposed side edges, each side edge being curled to form a tubular socket, the tubular socket at each edge extending throughout the full length of the plate or the edge thereof, the body portion of the plate joining the tubular sockets throughout the length of the plate, and one of said tubular sockets being arc-shaped in form. 45

8. A display device of the class described comprising a flexible sheet having relatively rigid end portions, an easel for supporting said sheet in extended position, said easel comprising a rod member of a length greater than the distance between the ends of said sheet, said member being placed under tension in coupling the ends thereof with the rigid ends of said sheet and maintained under tension when attached to the sheet to maintain the sheet in extended position, said easel including another rod forming a leg for supporting the sheet in upright position, a sheet metal plate coupling said member and leg together, opposed side edges of the plate being curled to form bearings, one for said member and the other for said leg, and said bearings being angularly disposed with reference to each other 55 to arrange the leg angularly with respect to said member. 55

9. A display device of the class described comprising a flexible sheet having relatively rigid end portions, an easel for supporting said sheet in extended position, said easel comprising a rod member of a length greater than the distance between the ends of said sheet, said member being placed under tension in coupling the ends thereof with the rigid ends of said sheet and maintained under tension 70

tension when attached to the sheet to maintain the sheet in extended position, said easel including another rod forming a leg for supporting the sheet in upright position, a sheet metal plate coupling said member and leg together, opposed side edges of the plate being curved to form bearings, one for said member and the other for said leg, said bearings being angularly disposed with reference to each other to arrange the leg angularly with respect to said member, and said plate being rotatable and longitudinally adjustable on said member.

JAY NOBLE EMLEY.
